UNITED STATES PATENT OFFICE

131,285

DESIGN FOR A COSTUME DRESS OR SIMILAR ARTICLE

Marie Miller, Los Angeles, Calif.

Application December 28, 1940, Serial No. 97,683

Term of patent 3½ years

To all whom it may concern:

Be it known that I, Marie Miller, a citizen of the United States, residing in Los Angeles, in the county of Los Angeles and State of California, have invented a new, original, and ornamental Design for a Costume Dress or Similar Article, of which the following is a specification, reference being had to the accompanying drawing, forming part thereof.

Fig. 1 is a front view of a costume dress or similar article showing my new design, and

Fig. 2 is a rear view thereof.

The dominant feature of my design resides in the combination, on the costume dress disclosed, of the vertical horn-shaped pockets disposed about the front and sides, as shown.

I claim:

The ornamental design for a costume dress or similar article, as shown and described.

MARIE MILLER.
